US0D1049734S

(12) **United States Design Patent** (10) **Patent No.:** **US D1,049,734 S**
(45) **Date of Patent:** **** Nov. 5, 2024**

(54) **DISPENSER**

(71) Applicant: **PepsiCo, Inc.**, Purchase, NY (US)

(72) Inventors: **Martin Eduardo Broen**, New York, NY (US); **Marco Cimatti**, Sleepy Hollow, NY (US); **Stephen Lim**, Chappaqua, NY (US); **Anton Ljunggren**, New York, NY (US); **Ivana Babic**, Milan (IT); **Martin Ivar Franzen**, Milan (IT)

(73) Assignee: **PepsiCo, Inc.**, Purchase, NY (US)

(**) Term: **15 Years**

(21) Appl. No.: **29/863,394**

(22) Filed: **Dec. 19, 2022**

Related U.S. Application Data

(63) Continuation of application No. 29/746,209, filed on Aug. 12, 2020, now Pat. No. Des. 972,876, which is a continuation of application No. 29/671,032, filed on Nov. 21, 2018, now Pat. No. Des. 893,236.

CLAIM

The ornamental design for a dispenser as shown and described.

DESCRIPTION

FIG. 1 is a top front perspective view of a dispenser showing the claimed design;

FIG. 2 is a bottom front perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The portions of the dispenser shown in broken lines form no part of the claimed design.

1 Claim, 8 Drawing Sheets
